UNITED STATES PATENT OFFICE

161,119

TEXTILE FABRIC OR THE LIKE

Claudia M. Ogden, Scottsdale, Ariz.

Application May 23, 1950, Serial No. 10,100

Term of patent 3½ years

(Cl. D92—1)

To all whom it may concern:

Be it known that I, Claudia M. Ogden, a citizen of the United States, residing at Scottsdale, in the county of Maricopa and State of Arizona, have invented a new, original, and ornamental Design for Textile Fabrics or the Like, of which the following is a specification, reference being had to the accompanying drawing, forming part thereof. The figure is a plan view of a textile fabric showing my new design. The dot and dash lines on the drawing outline a design unit, which unit is repeated in regular succession as indicated by the extensions beyond the unit boundaries.

I claim:

The ornamental design for a textile fabric or the like, as shown and described.

CLAUDIA M. OGDEN.
